ELECTRODE HOLDER

Ralph W. Welsh, Camden, N. J.

Application April 3, 1941, Serial No. 386,741

3 Claims. (Cl. 219—8)

My invention relates to equipment for electric welders, and has among its objects and advantages the provision of an improved electrode holder.

In the accompanying drawing:

Figure 1 is a plan view of a holder in accordance with my invention, with certain parts broken away for the sake of illustration;

Figure 2 is an enlarged sectional view taken along the line 2—2 of Figure 1;

Figure 3 is an enlarged sectional view of the chuck portion of the holder;

Figure 4 is a sectional view along the line 4—4 of Figure 3;

Figure 5 is a sectional detail view of the chuck cam;

Figure 6 is a sectional view taken along the line 6—6 of Figure 3;

Figure 7 is a sectional view of a modified form of the invention; and

Figure 8 is an elevational view of the structure illustrated in Figure 7.

In the embodiment selected to illustrate my invention, the chuck part 10 is connected with a handle 12 provided with a terminal 14 for connection with a current supply cable. Chuck 10 comprises a bronze body 16 enclosed in a wrapper or shell 18 of insulating material. Insulating material 18 is preferably of tubular contour.

Body 16 is provided with a V-shaped groove 20 extending longitudinally of the shell 18 but terminating short of one end of the body to provide a wall or abutment 22 constituting a stop for an electrode positioned in the groove 20. The electrode to be made secure in the chuck 10 is inserted through an opening 24 in a disc 26 of insulating material, which disc fits snugly inside the shell 18 and is fixedly secured to the body 16 by screws 28. Opening 24 is of sufficiently large diameter to accommodate electrodes of the largest size, and the walls of the V-shaped groove 20 provide a contour which constitutes a rest for effectively supporting electrodes of variable diameters.

Means for securing the electrode lying in the groove 20 comprises a cam 30 fixedly secured to the shell 18 by screws 32. Shell 18 is rotatable relatively to the body 16 about the axis of the disc 26 and the cam 30 is of such tapered contour as to engage the electrode and press it firmly against the walls of the groove 20. Fig. 4 illustrates the specific taper of the cam 30, the circle 34 representing a large diameter electrode engageable by the cam and the circle 36 representing a small diameter electrode also engageable by

the cam upon further rotation of the shell 18 relatively to the body 16.

The face of the cam 30 engageable with the electrodes is provided with helically contoured ribs 38 engageable with the electrodes for firmly urging the latter against the wall or stop 22. In operation, the electrodes, will, of course, be inserted through the opening 24 and either dropped upon or held against the wall or stop 22. However, when the shell 18 is rotated relatively to the body 16 in one direction the ribs 38 engage the electrodes and press them firmly against the wall or stop. In removing the electrodes, the shell 18 is rotated relatively to the body 16 in the opposite direction which moves the cam 30 out of pressure engagement with the electrode so that the latter is free to be removed from the chuck.

One end of the body 16 is provided with a threaded shank 40 threaded into a nipple 42 having a flange 44 located intermediate its ends. A washer 46 has peripheral engagement with the inner face of the shell 18 and is fixedly related thereto by screws 48. Washer 46 has its inner face fitting snugly on the nipple 42 but may be rotated relatively thereto.

A washer 50 is also fitted inside the shell 18 and lies adjacent the washer 46 and embraces the flange 44 on the nipple 42. Washers 46 and 50 are of insulating material, as well as the third washer 52 lying against the end of the shell 18 and fixedly secured to the washer 50 by rivets 54. Washer 52 has its inner face engaging the nipple 42 and lies against the face of the flange 44 opposite the face engaged by the washer 46. All the washers are fixedly secured into a unitary structure by bolts 56. Thus the three washers provide a connection between the shell 18 and the body 16 which permits the shell to be rotated relatively to the body but restrains the shell from relative longitudinal movement.

One end of the nipple 42 is externally threaded for connection with a socket 58 having a bore 60 for the reception of a sleeve 62 split longitudinally, as at 64. Socket 58 has flat and parallel faces 66 which fit between spaced faces 68 in one end of the tubular handle 12. Handle 12 is provided with aligned bores 70 for the reception of the sleeve 62 and the latter is provided with internal tapers 72 at each end for the reception of tapered washers 74 through which a bolt 76 is passed. The head of the bolt engages one washer and the other washer is threadedly connected with the bolt so that rotation of the bolt causes the washers to be pressed into the sleeve 62. Since the sleeve is slotted, tightening of the bolt

16 shifts the washers relatively to the tapers 72 and causes the sleeve 62 to expand against the face defining the bore 60 so as to effectively frictionally connect the socket 58 with the sleeve. The nipple 42 is also caused to frictionally engage the sleeve 62 by turning it into the socket 58 as far as it will go. Tightening of the bolt 16 fixedly secures all the parts so as to hold the chuck 10 at the desired angle with respect to the handle 12. Mere loosening of the bolt 16 permits the chuck to be pivoted about the axis of the bolt 16. The washers 74 are of insulating material, and the handle 12 comprises a tubular body 18 enclosed in an insulating covering 80. The end of the body 18 remote from the bolt 16 is provided with a wall 82 having a threaded socket 84 for connection with the threaded shank 86 of the terminal 14, the latter being provided with a threaded cable receiving bore 88.

Figs. 7 and 8 illustrate a plate 90 which may be secured to the disc 26 by a bolt 92. Plate 90 is provided with a bore 94 of small diameter which bore snugly receives an electrode of predetermined diameter. Thus plates 90 having bores 94 of diameters corresponding to the respective diameters of a series of electrodes may be mounted on the disc 26.

The holder embodies a chuck designed to accommodate electrodes of variable diameters, wherein the electrode mechanism is so devised as to effectively clamp the electrode in position, regardless of its diameter, in addition to affording a good grip on the electrode with respect to holding it in the groove 20 as well as against the wall or stop 22. The chuck 10 may be easily and quickly adjusted to any desirable angle with respect to the handle 12.

Without further elaboration, the foregoing will so fully illustrate my invention that others may, by applying current knowledge, readily adapt the same for use under various conditions of service.

I claim:

1. In an electrode holder, the combination of a body having a groove defined by converging walls, a shell of insulating material rotatable relatively to said body about the axis of said groove, and a cam fixedly carried by said shell arranged for pressure engagement with the electrode to press the electrode against said walls.

2. In an electrode holder, the combination of a body having a groove defined by converging walls, a shell of insulating material rotatable relatively to said body about the axis of said groove, a cam carried by said shell arranged for pressure engagement with the electrode to press the electrode against said walls, said body being provided with a stop located at one end of said groove for engagement by the electrode, and said cam being provided with structural irregularities angled to engage the electrode and press the latter firmly against said stop.

3. In an electrode holder, the combination of a body having a groove defined by converging walls, a shell of insulating material rotatable relatively to said body about the axis of said groove, a cam carried by said shell arranged for pressure engagement with the electrode to press the electrode against said walls, said body being provided with a stop located at one end of said groove for engagement by the electrode, said cam being provided with structural irregularities angled to engage the electrode and press the latter firmly against said stop, a disc of insulating material mounted on said body and having an opening located in alignment with said groove for the reception of the electrode, a flange on said body, and insulative washers fixedly secured one to the other and to said shell and coacting with said flange to restrain the shell from relative movement longitudinally of the axis of said groove.

RALPH W. WELSH.
